(57) **CLAIM**

The ornamental design for a plumbing fixture, as shown and described.

DESCRIPTION

In a preferred embodiment, the nature of this product is as a plumbing fixture in the form of a bathing tub or portion thereof.

FIG. 1 is a left, top, front perspective view of a plumbing fixture according to our new design;

FIG. 2 is a left, top rear perspective view thereof;

FIG. 3 is a top plan view thereof;

FIG. 4 is a sectional view taken along line 4—4 of FIG. 3;

FIG. 5 is a left, top, front perspective view of a plumbing fixture according to another embodiment of our new design;

FIG. 6 is a top plan view thereof; and,

FIG. 7 is a sectional view taken along line 7—7 of FIG. 6.

The broken line representations in the figures, are for the purpose of illustration only, and form no part of the claimed design.
